UNITED STATES PATENT OFFICE.

CHARLES CLIFFORD LAWRENCE, OF NAPOLEON, INDIANA.

MAIL-CATCHER.

1,115,842.

Specification of Letters Patent.

Patented Nov. 3, 1914.

Application filed January 27, 1914. Serial No. 814,721.

To all whom it may concern:

Be it known that I, CHARLES CLIFFORD LAWRENCE, citizen of the United States, residing at Napoleon, in the county of Ripley 5 and State of Indiana, have invented certain new and useful Improvements in Mail-Catchers, of which the following is a specification.

This invention relates to a mail catcher, 10 and the principal object of the invention is to provide a mail catcher which is so constructed that when the sack is caught, the holding and catching means will swing to an inoperative position and thus move the 15 catching and delivering arms to a position where they will not extend toward the train or station.

Another object of the invention is to so construct the catching and delivering means 20 that they will move simultaneously to an operative or inoperative position.

Another object of the invention is to so construct the device that the trigger which holds the arms in an operative position will 25 be released by a sack caught by the catching element of the device.

Another object of the invention is to so construct the device that when a sack is engaged by the catching means, the holding 30 means will turn in the direction to permit the sack to be easily removed from the holding means.

Another object of the invention is to so construct the catching arm that when the 35 trigger is released, the weight of the catching arm will cause the catching arm to swing to a lowered position and transmit rotary motion to the shaft of the supporting arms so that the supporting arms will swing to an 40 inoperative position.

Another object of the invention is to so construct the device that the train element and track element will be constructed along the same lines and thus permit the mail 45 catcher to be very cheaply made, the parts being interchangeable.

Another object of the invention is to so construct and mail catcher that the device will be very strong and durable and not 50 liable to easily get out of order.

This invention is illustrated in the accompanying drawings wherein—

Figure 1 is a view in elevation showing the train device and track device in an in-

operative position; Fig. 2 is a view showing 55 the mail catcher in top plan and in an operative position, the car being shown in longitudinal section and the upper portion of the frame of the station device being broken away; Fig. 3 is a view in elevation looking 60 from the left of Fig. 2 with the holding arms of the station device shown broken away. Fig. 4 is a perspective view of the station device in an operative position.

The train device is mounted in the doorway 10 of the mail car 11, and is partially carried by the standard 12 and partially by the side 13 of the frame which forms the doorway. The holding means is entirely carried by the standard 12 by means of bearing brackets 14 which rotatably support the shaft 15 from which there extends the upper and lower arms 16. A beveled gear 17 is rigidly mounted upon the shaft 15 at a point intermediate its length so that rotary motion may be transmitted to the shaft 15. Fingers 18 are pivotally mounted in longitudinally-extending pockets formed in the arms 16 and extend beyond the outer ends of the arms so that the fingers may engage 80 the upper and lower eyes 19 of a mail bag 20 and releasably hold the mail bag in the vertical position shown in Fig. 1. Springs 21 are mounted in the housings and engage the fingers 18 to normally hold the fingers in 85 a substantially horizontal position. These fingers are prevented from being moved beyond the horizontal position by the heels 22 which engage the housings in the same manner as shown at the right of Fig. 3. It 90 should also be noted that the springs 21 are also mounted in the housings in the same manner as shown in Fig. 3. In order to connect the mail sack with the fingers, it is necessary to move the fingers against the 95 tension of the springs 21 and therefore there has been provided extensions 23 which may be grasped by the mail clerk when it is desired to move the fingers.

The shaft 24 which forms part of the 100 catching means of the train element has one end portion journaled in the standard 12 and the other end portion journaled in the sleeve 25 which is secured to the frame of the doorway by means of bolts 26 which 105 pass through the arms 27. A bevel gear 28 is rigidly mounted upon this shaft 24 beyond the standard 12 and meshes with the bevel

gear 17 so that when the shaft 24 is rotated, rotary motion will be transmitted to the shaft 15. A sleeve or horizontal arm 29 is connected with the shaft 24 by means of the 5 bracing legs 30 and carries a jaw 31 adjacent its outer end and a block 32 adjacent one of the legs 30. The trigger 33 which is pivotally connected with the jaw 31 by means of the pin 34 is pivotally connected 10 with a link 35, which link is secured to the leaf spring 36 carried by the block 32. This spring 36 will therefore normally hold the trigger in the position shown in Fig. 1. The second jaw 37 is secured to the outer end 15 of the stem 38 and is provided upon its inner face with a rack 39 which may be engaged by the trigger as shown in Fig. 2 and the trigger thus held in a position to hold 20 the two jaws in an open position. This stem 38 extends through the sleeve 29 and through an opening formed in the shaft 24. A spring 40 is mounted upon the stem 38 between the sleeve 29 and abutment 41 and normally holds the stem in the position 25 shown in Fig. 1. A lug 42 is provided at the inner end of the stem 38 and is engaged by a sliding pin latch 43 which is slidably mounted in a bracket 44 carried by the sleeve 25. A spring 45 is mounted upon the 30 pin 43 and engages an abutment 46 to yieldably hold the pin in the normal position shown Fig. 2.

After the mail sack has been connected with the fingers 18, the handle is grasped 35 and the shaft 24 is rotated to swing the catching device to the position shown in Fig. 2 and rotate the shaft 15 and swing the arm 16 to the position shown in this figure. The stem 38 is then moved outwardly until 40 the lug 42 is engaged by the latch pin 43 and the trigger is moved to the position shown in Fig. 2 to hold the jaw in spaced relation. If desired, the stem 38 can be moved to the extended position and the jaws held 45 in spaced relation by means of the trigger before the shaft 24 is rotated to extend the catching device. When a mail sack is caught by the catching device, the sack strikes the trigger and moves the trigger to the position 50 shown in Fig. 1. The spring 40 will then move the stem 38 to bring the jaws in tight engagement with the mail sack and at the same time move the lug 42 out of engagement with the pin 43. The weight of the 55 catching device will then cause the catching device to swing downwardly to the position shown in Fig. 1 and turn the shaft 15 to swing the arms 16 into the car. The mail sack which is held by the arms 16 will be 60 engaged by the catching device of the track element and as the arms swing inwardly, the mail sack will be drawn off of the fingers 18. As these arms turn in the direction of the rear end of the car, the mail sack may 65 be easily removed from the fingers and there

is no danger of the eyes 19 binding upon the fingers 18 and thus causing the fingers or sack to be damaged.

The station element of this mail catcher is very similar to the train device. The standards 48 and 49 are slidably mounted 70 in the supports 50 and are provided with racks 51 which are engaged by the gears 52. These gears 52 are rigidly mounted upon the shaft 53 between the bearings 54 which rotatably support the shaft 53. A handle or crank 55 is provided so that the shaft 53 may be rotated to raise the standards to such a height that the station element will be in the proper position to coöperate with 80 the train element. The upper end portion 56 of the standard 48 is bent toward the standard 49 as shown at 57 and then carried parallel to the standard 49, and has its upper end connected with the upper end of the 85 standard 49 by means of a cross bar 58.

The vertical shaft 59 which corresponds to the shaft 15 is rotatably connected with the standard 49 by means of the bearing bracket 60 and carries arms 61 which correspond to the arms 16. Fingers 62 which correspond to the fingers 18 are pivotally mounted in the outer end portions of the 90 housings 63 formed in the arms 61 and are provided with heels 64 which limit the pivotal movement of the fingers 62. Springs 65 are secured to the pins 66 carried by the fingers 62 and are passed around the pins 67 and secured to the pins 68 adjacent the inner ends of the housings 63. Extensions 69 which form hand-holds are provided so that the fingers 62 may be moved to a position 95 to permit the station master to connect the pins 62 with the eyes 70 of the mail bag 71.

The shaft 72 which corresponds to the shaft 24 is mounted between the upper end 105 portions of the standards 48 and 49 and has one end journaled in the sleeve 73 of the bearing bracket 74 and has its opposite end journaled in the standard 49. A bevel gear 110 75 is rigidly mounted upon the end of the shaft 72 which extends beyond the standard 49 and meshes with the bevel gear 76 carried by the shaft 59 so that rotary motion may be transmitted from the shaft 72 to the 115 shaft 59. The jaw 77 extends from the outer end of the sleeve 78 which is connected with the shaft 72 by means of the bracing legs 79. The stem 80 which carries the movable jaw 81 extends through the sleeve 78 and through an opening formed in the shaft 72. A spring 82 is mounted upon the stem 80 and engages the abutment 83 to normally 120 hold the stem 80 in the position shown in Fig. 1. In order to hold the jaws 78 and 81 in an open position, there has been provided a trigger 84 which is pivotally mounted in an opening 85 formed in the jaw 77 and engages the rack 86 formed upon the inner face 125 of the jaw 81. This trigger 84 is pivotally 130

connected with a link 87 which is connected with a leaf spring 88 carried by the block 89. A latch pin 90 is slidably supported by means of a bracket 91 secured to the sleeve 5 73 and is yieldably held in a position to engage the lug 92 formed upon the inner end of the stem 80 by means of a spring 93 which is mounted upon the pin 90 and engages the abutment 94 formed thereon. It will thus 10 be seen that this station element is constructed very similar to the train element.

When this mail catcher is in operation, the mail sacks 20 and 71 are connected with the fingers 18 and 62 and after the jaws 15 have been opened and secured in the open position by means of the triggers 33 and 84, the shafts 24 and 72 are rotated by means of the handles or levers 47 and 95 to swing the catching arms outwardly and rotate the 20 shafts 15 and 59 to swing the sack-holding arms outwardly. The latch pins 43 and 90 will engage the lugs 42 and 92 to hold the catching arms in the raised position and prevent them from swinging downwardly 25 before the mail sacks have been caught. The station device has its standards adjustably mounted so that when this mail catcher is erected, the standards of the station device may be adjusted to a suitable height to 30 cause the catching and holding arms of the train and station devices to assume the positions shown in Fig. 3 when the train passes the station. It should also be noted that if desired, the station master can raise and 35 lower the station device by turning the shaft 53 in order that he may conveniently reach the catching and holding arms when it is necessary to place a sack in position or when it is necessary to make repairs.

40 When the train approaches the station, the catching arm of the station device passes above the catching arm of the train device and will engage the sack carried by the fingers 18. At the same time a catching arm 45 of the train device will engage the sack carried by the fingers 62. As these sacks engage the triggers 33 and 84, the triggers will be moved to release the movable jaws and permit the springs 40 and 82 to move the stems 38 and 80 inwardly. This will cause the stems to be released from the latches 43 and 90, and the catching arms will then swing downwardly to rotate the shafts 24 and 72, thus transmitting rotary motion to 50 the shafts 15 and 59 to swing the sack-holding arms inwardly. It will thus be seen that when the mail bags are caught by the engaging arms, the sack caught by the train element will be swung into the car, and the 55 sack caught by the station element will be swung downwardly to a position between the standards 48 and 49 and above the shaft 53. The mail bags can now be removed by the railway mail clerk and by the station 60 master and new sacks connected with the

supporting arms if desired. This mail catcher will be very durable since the parts are very strong and comparatively few in number, and it will thus be seen that the mail catcher can be cheaply made.

It will also be readily seen that with this device most of the parts of the station device and train device will be interchangeable since the station device and train device are practically duplicates of each other. 70 The only difference between the two devices is the substitution of the standards 48 and 49 for the standard 12 and car frame 13 and the provision of the supports and adjusting means for the standards 48 and 49. 75

What is claimed is:

1. A mail bag holding and catching device comprising a support, a vertical shaft rotatably connected with said support, arms extending from said shaft, sack-holding means yieldably connected with said arms, a horizontal shaft rotatably connected with said support, means for transmitting rotary motion from said horizontal to said vertical shaft, a catching arm extending from said horizontal shaft and provided at its free end with means for engaging a mail bag, means for releasably holding the bag-engaging means in an open position, said means pivotally moving to a released position by a mail bag caught by said catching arm, means for engaging the catching arm when in an extended position to hold the catching arm in a raised position and prevent rotation of said horizontal shaft, and means for moving 100 said catching arm out of engagement with said last-mentioned means when a sack is caught to permit the catching arm to swing downwardly and rotate said horizontal shaft to transmit rotary motion to said vertical 105 shaft and rotate the same to swing said sack-holding arms inwardly.

2. A mail bag holding and catching device comprising a support, bag-holding means rotatably connected with said support, 110 bag-catching means rotatably connected with said support, means for transmitting rotary motion from said catching means to said holding means, means for releasably holding said catching means in an extended position, 115 and means operated by a sack engaged by said catching means for permitting said catching means to move out of engagement with said last-mentioned means when a sack is caught and moved to an inoperative position and rotate said sack-engaging means to cause the sack-holding means to swing to an 120 inoperative position.

3. A mail bag holding and catching device comprising a support, a horizontal shaft 125 rotatably carried by said support, a sleeve extending from said shaft, a jaw at the outer end of said sleeve, a stem slidably mounted in said sleeve and extending through an opening formed in said shaft, a jaw at the 130

outer end of said stem, a trigger carried by one of said jaws for engaging the other of said jaws for holding said jaws in an open position, resilient means for normally holding said stem in a position to hold said jaws in a closed position, means releasably engaging said stem when said stem is extended and said shaft rotated to hold said catching means in a raised position, bag - holding means rotatably connected with said support, and means for transmitting rotary motion from said shaft to said bag-holding means, said trigger being moved to a released position by a mail bag passing between said jaws and said resilient means then moving said stem inwardly out of engagement with the means engaging its inner end to permit said sleeve and stem to swing downwardly and rotate said shaft to transmit rotary motion to said bag-holding means and swing the same to an inoperative position.

4. A mail bag holding and catching device comprising catching means including a rotatably mounted shaft, a sleeve connected with said shaft and extending at substantially right angles thereto, a jaw at the outer end of said sleeve, a stem slidably mounted in said sleeve and extending through an opening formed in said shaft, a jaw at the outer end of said stem, a trigger carried by one of said jaws for engaging the other of said jaws to releasably hold said jaws in an open position, a spring mounted upon said stem having one end engaging the inner end of said sleeve and the other engaging an abutment formed upon said stem for normally urging said stem inwardly to hold said jaws in a closed position, means for engaging said stem when said stem is extended and said catching means raised to an inoperative position for releasably holding the catching means in an operative position, sack-holding means rotatably connected with said support, and means for transmitting rotary motion from said shaft to said holding means whereby when a sack is caught by said catching means and said stem moved out of engagement with the means engaging its inner end said catching means will swing downwardly and rotate its shaft to transmit rotary motion to said holding means and swing the same to an inoperative position.

5. A mail bag holding and catching device comprising a support, a bearing bracket carried by said support, a rotatably mounted shaft having one end mounted in said bearing of said bracket, a sleeve connected with said shaft, a stem slidably mounted in said sleeve, jaws carried by the outer end portions of said sleeve, a stem, means for yieldably holding said stem in a position to normally hold said jaws in a closed position, means for releasably holding said jaws in an open position, a bracket car-

ried by said bearing bracket, a latch pin slidably carried by said last-mentioned bracket, a spring mounted upon said pin and engaging an abutment provided thereon for yieldably holding said pin in a normal position, a lug extending from the inner end of said stem for engagement with said latch pin to hold said stem in a raised position and prevent rotation of said shaft, the spring mounted upon said stem moving said stem out of engagement with said latch pin when a mail sack is caught between said jaws to permit said stem to swing downwardly and rotate said shaft, a sack-holding means rotatably connected with said support and means for transmitting rotary motion from said shaft to said sack-holding means.

6. A mail bag holding and catching device comprising a support, bag catching means carried by said support and including a rotatably mounted shaft, a sleeve connected with said shaft, a stem slidably mounted in said sleeve, jaws extending from the outer end portions of said sleeve and stem, resilient means for normally holding said stem in a position to hold said jaws in a closed position, a trigger pivotally connected with the jaw of said sleeve, a spring carried by said sleeve, a link carried by said spring and pivotally connected with said trigger, said spring normally holding said trigger in an inoperative position, means for releasably engaging said stem for holding the stem in a raised position, said stem being moved out of engagement with said last-mentioned means when a mail bag caught between said jaws moves said trigger out of engagement with the jaw of said stem and swing downwardly to rotate said shaft, sack-holding means rotatably connected with said support, and means for transmitting rotary motion from said shaft to said sack-holding means.

7. A mail bag holding and catching device comprising a support, a shaft rotatably connected with said support, a sleeve, arms connected with said sleeve with said shaft and holding the same in spaced relation thereto, a stem slidably mounted in said sleeve and extending through an opening formed in said shaft, an abutment carried by said stem between said sleeve and shaft, a spring mounted upon said stem between said sleeve and abutment, jaws carried by the outer end portions of said sleeve and stem, means for holding said jaws in an open position, said spring moving said stem inwardly to move said jaws to a closed position when said last-mentioned means is moved to a released position by a sack caught between said jaws, means for releasably engaging the inner end portions of said stem for holding said stem in a raised position, said stem moving out of engage- 130

ment with said last-mentioned means when said sack has been caught between said jaws and swung downwardly to rotate said shaft, sack-holding means rotatably connected 5 with said support, and means for transmitting rotary motion from said shaft to said sack-engaging means.

8. A mail bag holding and catching device comprising a support including standards, sack-catching means rotatably connected with said support between said standards, sack-holding means rotatably connected with one of said standards, means for transmitting motion from said catching to 15 said holding means whereby when said

catching means swings to an inoperative position after catching a sack said holding means will be swung to an inoperative position, means for releasably holding the catching means in an operative position, and 20 means for releasably holding said catching means in a position for engagement by said last mentioned means.

In testimony whereof I affix my signature in presence of two witnesses.

CHARLES CLIFFORD LAWRENCE.
